UNITED STATES PATENT OFFICE.

MOSES C. NIXON, OF LIMA, OHIO.

BALING-PRESS.

1,120,402.

Specification of Letters Patent.

Patented Dec. 8, 1914.

Application filed September 10, 1914. Serial No. 861,040.

To all whom it may concern:

Be it known that I, MOSES C. NIXON, a citizen of the United States, residing at Lima, in the county of Allen and State of Ohio, have invented new and useful Improvements in Baling-Presses, of which the following is a specification.

The present invention relates to improvements in baling-presses; the object being to provide an improved power transmitting mechanism and other improvements as may hereafter appear; and consists, preferably, in the construction hereinafter described, which may be varied without departing from the spirit of my invention.

In the drawings, Figure I is a side elevational view of a baling-press embodying my improvements, parts being broken away to better show certain features; Fig. II is a plan view of Fig. I, also with parts broken away; Fig. III is a side elevational view of a detached part of the power transmitting mechanism; Fig. IV is a top view of Fig. III; Fig. V is a side view of the sprocket wheel with gear attached, and Fig. VI is an edge view of sprocket wheel and sectional view of gear attached.

In the drawings, similar numerals of reference indicate corresponding parts in the different views, and, referring to the same, 1 is the body or case that forms the baling-chamber of a baling-press and 2 is a plunger. Secured to and forming an extension below the baling-case are Z bars 3, the lower flange of which extends inwardly and forms the supports for the plunger. The plunger consists of a base-frame 4, to which are secured two uprights or standards 5, and to these uprights is secured plate 6, which extends transversely across the baling-chamber and forms the compression front of the plunger. Frame 4 is composed of two side bars or members 7, to the rear extremities of which are mounted anti-friction rollers 8 which roll on the lower flange 3^a of Z bars 3, the frame 4 being operated beneath the bottom 10 of the baling-case. Adjacent the forward end of member 7 are mounted anti-friction rollers 9 which are adapted to roll on the flanges 3^a and beneath the bottom 10 of the baling-case. A suitable head 11 is secured to the forward end of the side bars 7 and to this head is pivotally secured the pull-bar or pitman 12.

Extending from the front end of the baling-case is a frame 13, which in this case

is formed by the continuation of the Z bars 3. On each side near the forward end of frame 13 are firmly secured brackets 14, (more clearly shown in Figs. III and IV) 60 each of those brackets is provided with two upwardly extending lugs 15, also secured to and extending inwardly from the brackets are stub-shafts 16. Revolubly mounted on these stub-shafts are sprocket wheels 17, 65 which are provided with hubs or sleeves 18, (shown in Fig. VI) and to these hubs are secured gears 19, as by keys 20, or, if preferred, these wheels and gears may be cast as one piece, in either case as the gears 70 revolve the sprocket wheels are revolved with them. Opposite each other and rearward of brackets 14 are brackets 21, which are provided with oblong holes 22, and are secured to the frame 13 by bolts 23. Secured 75 to and extending inwardly from brackets 21 are stub-shafts 24, and revolubly mounted thereon are sprocket wheels 25. The sprocket wheels 17 and 23 are retained on their respective shafts by washers 26, which 80 are secured in place by bolts 27. On the two sets of sprocket wheels are endless sprocket chains 28, which are connected by a wrist-pin 29. This wrist-pin is suitably connected with the pull-bar 12, so when the 85 sprocket wheels and chains are driven a reciprocating movement is imparted to the plunger. In Fig. I the pull-bar 12 is shown as connected with the lower part of the endless chain, which produces the retracting 90 movement of the plunger, as it can be shown in that position, the upper part being obscured by the frame.

Brackets 14 and 21 are provided with rods 30 and 31, (see Figs. III and IV) one 95 of each set of these rods being provided with right and the other left hand threads with a suitable turn-buckle or sleeve 32 in connection therewith whereby brackets 21 may be moved and in connection with the 100 oblong holes 22 and bolts 23 held in position to give the proper tension on the sprocket chains 28.

Mounted upon shaft 33 a belt-pulley is shown, which is adapted to receive and 105 transmit power to gear-wheel 34 by means of gear-pinion 35. Gear-wheel 34 is secured to shaft 36, which is journaled in journal boxes 37, said boxes being placed between lugs 15 on brackets 14 and secured to the 110 frame 13, the object of these lugs being to prevent misplacement of the boxes or their

moving lengthwise on the frame. To shaft 36 are secured gear-pinions 38 and through them power is transmitted to gears 19 and as these gears are secured to the sprocket wheel 17, it is obvious that they will transmit power to the sprocket chains 28 and through them to the pull-bar or pitman 12 and thereby cause the plunger to be reciprocated.

10 The advantage of the rigidly supported stub shaft carrying loosely mounted sprocket and gear wheels on a single hub over that where the sprocket wheel is secured to the projecting end of a loosely mounted rotatable shaft in a baling press is that when the charge is being pressed the resistance is great, causing the rotatable shaft to pinch in its bearings and wear out of alinement; while with the hub rotating on a rigidly 15 supported shaft the pinching is avoided, friction and wear reduced and the life thereof prolonged.

I claim:

1. A baling-press having a baling-case 25 and a frame extending therefrom, stub-

shafts rigidly supported by said frame, sprocket wheels rotatably mounted on said shafts, part of which are arranged as drivers, gears secured to said drivers for actuating the same, parallel sprocket chains 30 mounted on said wheels, a reciprocating plunger, and means connecting said chains and plunger whereby the latter may be reciprocated.

2. A baling-press having a baling-case 35 and a frame extending therefrom, stub-shafts rigidly supported by said frame, sprocket wheels rotatably mounted on said shafts, part of which are provided with hubs or sleeves and arranged as drivers, 40 gears secured to said sleeves for actuating said drivers, parallel sprocket chains mounted on said wheels, a reciprocating plunger, and means connecting said chains and plunger whereby the latter is reciprocated.

MOSES C. NIXON.
